UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

EXPANDED METAL STRUCTURE.

1,088,951.

Specification of Letters Patent.

Patented Mar. 3, 1914.

Application filed June 21, 1911. Serial No. 634,617.

To all whom it may concern:

Be it known that I, HERBERT E. WHITE, a resident of Youngstown, in the county of Mahoning and State of Ohio, have invented 5 a new and useful Improvement in Expanded Metal Structures, of which the following is a full, clear, and exact description, reference being had to the accompanying drawings, forming part of this specification, in 10 which—

Figure 1 is a perspective view illustrating the first step in the manufacture, in accordance with my invention. Fig. 2 is a plan view, and Fig. 3 is a side view, illustrating 15 the cutting operations. Fig. 4 is a cross-sectional view showing the cut blank before expanding. Fig. 5 is a plan view of a portion of the expanded blank or structure, and Fig. 6 is a cross-section of the expanded 20 blank or structure.

My invention has relation to expanded metal structures, and is designed to provide a structure of this character which will possess a maximum stiffness and rigidity; 25 which can be readily manufactured; and which is adapted to a wide variety of uses.

In producing a structure embodying my invention, I first take a flat metal sheet and subject it to the action of dies to form there- 30 in the longitudinally extending, relatively deep, parallel ribs 2, as shown in Fig. 1. The sheet may be of any desired width and may be formed with any number of these parallel ribs, and the form of the ribs may 35 be widely changed without departing from my invention. I next cut or slit the blank, the first cutting consisting of a series of alined longitudinal cuts 3, formed centrally between adjacent ribs, or between the 40 pairs of adjacent ribs, and then make subsequent parallel cuts 4 at each side of the central line of cuts, each successive cut acting to stretch the metal between the cuts down- 45 wardly, so that the blank assumes the V- shape, shown in Figs. 2, 3 and 4. Figs. 2 and 3 show the manner in which the cuts are successively made, until finally substantially the entire space between the adjacent ribs is cut and stretched so that a cross-section 50 through two adjacent ribs and the intervening slotted portion, taken at any point through the length of the sheet, will have the general V-form shown in Fig. 4. Each series of cuts or slits is staggered or alter- 55 nated with respect to those of the adjacent

series, so as to produce a diamond mesh. This cutting or slitting can be very accurately done, since the ribs 2 act to greatly increase the stiffness of the sheet and permit it to be rigidly guided and held to the action 60 of the cutting dies. When the cutting or slitting has been completed, the blank is expanded laterally to bring the cut or slit portion or portions into a substantially flat plane, as shown in Figs. 5 and 6. The ex- 65 panded structure then shows, between each pair of ribs, an expanded section of diamond mesh form with the slats or bars of the mesh inclined at a considerable angle to the flat plane of the structure, the bars 6 at one 70 side of the longitudinal central line a of the expanded portion, being inclined reversely to the bars 7 at the opposite side of such central line. This inclination of the mesh bars, and particularly the reverse inclina- 75 tion at opposite sides of the central line a, greatly increases the strength and rigidity of the structure.

It will be readily understood that while I have shown a structure having only two 80 ribs, that the structure may be of any de- 85 sired width within practical limits, with an expanded section between each two adjacent ribs. It will also be clear that inasmuch as the slotted metal is stretched, as above de- 90 scribed, it will be made thinner, and as a consequence, the expanded web between the ribs will be thinner than the ribs themselves. At least two advantages result from this 95 construction. In the first place, the stretching action, to a certain extent, hardens the metal, which will give rigidity to the web portion, and secondly a decided saving of material is effected, without weakening the structure at any important point. For ex- 100 ample, it will be evident that the ribs must be depended upon for support, and these ribs are in no way weakened. Moreover, they are not shortened, but the original length of the sheet is maintained. The webs of expanded metal between the ribs merely act as stays, and therefore do not have to be as strong. The stretching of the metal and the consequent thinning thereof occurs only in the expanded 105 portion. At the same time, rigidity of said expanded portion is maintained by the hardening of the metal above mentioned. At- 110 tention is also called to the fact that the junction between the expanded metal web and the ribs is secured by reverse bends,

shown in Figs. 5 and 6, which are formed in the unslotted metal directly alongside the ribs 2. These bends serve a two-fold purpose. In the first place, they obviate the 5 danger of breakage at the spaced points where the expanded metal joins the uncut portion, and furthermore they materially strengthen the ribs against bending in either direction.

10 The structure formed in the manner above described can be used for a variety of purposes, such as lathing, concrete reinforcement, etc. When deep ribs are formed intermediate the expanded sections, such as those 15 illustrated at 2 in the drawings, the structure may be used as a self furring lath, the ribs 2 acting as furring strips or ribs.

I do not claim herein the novel method of manufacturing my improved structure, as 20 such method forms the subject matter of a Patent No. 1,057,694, dated April 1, 1913.

What I claim is:

1. As an article of manufacture, a metal structure, consisting of a single sheet having 25 spaced high stiffening ribs and a web between the ribs and integral therewith, said web comprising sinuous strands or ribbons disposed substantially longitudinally of the ribs between the same and each being alternately and integrally joined at spaced points to the adjacent strands or ribbons on opposite sides of it, the said strands or ribbons being set at an opposite inclination from the center of the web and the outermost being 35 furthermore integrally joined at spaced points to the edges of the ribs, said strands or ribbons being elongated and thereby of thinner material than the material of the ribs.

40 2. An expanded sheet metal product including a plurality of spaced high ribs, and expanded open-mesh sections between said ribs and integral therewith, each of which sections consists of connected elongated 45 strands, the strands at one side of the longi-

tudinal center of the section having an inclination reverse to the inclination of the strands at the opposite side of said center.

3. As an article of manufacture, a metal structure consisting of a single sheet having 50 a plurality of spaced high stiffening ribs having reverse longitudinal beads, the outer sides of which are set at an inclination, and a web between the ribs, said web comprising strands or ribbons that are disposed substantially longitudinally of the ribs between the same and being integrally joined to each other, the outermost strands or ribbons having spaced portions also integrally joined to the edges of the outer sides of the beads, the 60 portions so joined to the beads being disposed longitudinally of the beads and set at substantially the same inclination as the outer sides thereof.

4. As an article of manufacture, a metal 65 structure consisting of a single sheet having a plurality of spaced stiffening ribs and a web between the ribs, said web comprising strands or ribbons that are disposed substantially longitudinally of the ribs between 70 the same and being sinuous, each strand or ribbon being alternately and integrally joined at spaced points to the adjacent ribbons on opposite sides of it, the outermost strands or ribbons having spaced portions 75 also integrally joined to the edges of the ribs, the portions so joined to the ribs being disposed longitudinally of the ribs, and said ribs having their margins adjacent to said juncture with the strands provided with reverse longitudinal beads, the strands or ribbons being of material that is thinner than the ribs.

In testimony whereof, I have hereunto set my hand.

HERBERT E. WHITE.
